DISPENSING CLOSURE

Woodrow S. Wilson, Pasadena, and Edward G. Akers,
Downey, Calif., assignors to Polytop Corporation,
Slaterville, R.I., a corporation of Massachusetts

Filed Apr. 26, 1965, Ser. No. 84,961

Term of patent 14 years

(Cl. D58—26)

FIG. 1.

FIG. 2.

FIG. 3.

FIG. 4.

FIG. 5.

FIG. 6.

FIG. 1 is an isometric view of a dispensing closure showing our new design;

FIG. 2 is another isometric view with the spout in dispensing position;

FIG. 3 is a top plan view with the spout in a closed position;

FIG. 4 is a left side elevational view thereof;

FIG. 5 is a front elevational view thereof; and

FIG. 6 is a rear elevational view thereof.

We claim:

The ornamental design for a dispensing closure, substantially as shown.
